F. M. SLOUGH.
TELEPHONE EXCHANGE SYSTEM.
APPLICATION FILED DEC. 5, 1917.

1,427,170.

Patented Aug. 29, 1922.

UNITED STATES PATENT OFFICE.

FRANK M. SLOUGH, OF ROCHESTER, NEW YORK, ASSIGNOR TO THE STROMBERG-CARLSON TELEPHONE MANUFACTURING COMPANY, OF ROCHESTER, NEW YORK, A CORPORATION OF NEW YORK.

TELEPHONE-EXCHANGE SYSTEM.

1,427,170.

Specification of Letters Patent. Patented Aug. 29, 1923.

Application filed December 5, 1917. Serial No. 205,599.

To all whom it may concern:

Be it known that I, FRANK M. SLOUGH, a citizen of the United States, residing at Rochester, in the county of Monroe and State of New York, have invented certain new and useful Improvements in Telephone-Exchange Systems, of which the following is a full, clear, and concise description.

It has been a common practice in operating telephone switchboards to divide the same up into sections at each of which is located a multiple jack for each of the telephone lines, and at some of these sections multiply connected signal lamps have been used to indicate a call originating on the associated telephone line.

In such switchboards of the art, the lamps of the different switchboard sections associated with the same telephone line operate simultaneously upon the initiation of a call by a subscriber on the line, and it often happens that several operators will attempt to answer the same call.

It is an object of this invention to prevent much of this confusion and to provide for more efficient team work between the operators. I, therefore, provide for each operator's position a number of answering jacks, and for each an associated line lamp. Line and cut-off relays are permanently associated with the answering lamp and answering jack to control the operation of this lamp. The number of answering jacks with their associated lamps provided for a position may vary, and may be between 100 and 200 in number.

The telephone lines leading into the switchboard preferably are permanently associated with multiply connected switchboard jacks located each on a different section of the switchboard, and at one or more of these switchboard jacks I provide multiple signal lamps. Now, by what is known in the art as "cross-connecting," I may associate any line together with its connected multiple switchboard jacks and their associated signal lamps to an answering switchboard jack together with its answering signal lamp. What I term as the multiple jacks and their associated lamps of any line always therefore maintain a fixed position in the switchboard, but as the cross-connection may be varied to associate the said line with different answering jacks and

associated lamps variously located on the 55 different operators' positions, such answering jacks and lamps may not at all times be associated with the same telephone line; also, conversely the said telephone line may not always have the same answering jack and 60 lamp, and it follows that since the line and cut-off relays are permanently associated with the answering jack and lamp, the multiple lamps controlled by a given line and cut-off relay at one time may be, by a different cross-connection, at another time controlled by a different line and cut-off relay.

It has been a common practice in systems of the art operated under the above plan to occasionally cross-connect some of the 70 lines, whereby an over-loaded position may have relief obtained through transferring the answering terminals and associated lamps of some of the busy lines to other positions. Although, this has been of considerable benefit it is not always possible to accurately gauge the number of calls originating on such a small group of lines as is associated with an operator's position, and much dependence is therefore had 75 upon the operators at either side of an operator at a temporarily over-loaded position reaching over and answering some of the calls on such a position.

It is an object of my invention to characterize the signal indication given by any of the switchboard lamps to indicate the measure of the loaded condition of the operator's position wherein the lines with which these lamps are associated have their 85 answering terminals. Thus, the operator observing calls on the positions to either side can give assistance to the operator most in need of such assistance, the character of the signal given by the lamps on each of these 90 positions indicating the extent of the over-loaded condition, if any.

It is a further object of my invention to extend this over-load signal characterization to the multiply connected lamps associated with multiple jacks of a line which has its answering terminals in such an over-loaded position, whereby the operators at the switchboard sections wherein these multiple lamps appear can distinguish between 100 signals of lines having their answering terminals in relatively idle positions, and signals of lines having their answering terminals

nals in relatively busy or over-loaded positions. The characterization of signal lamps above referred to is variable, and the intensity of the signal depends, directly in the 5 system of my invention, to the degree of over-load on the answering switchboard position.

I also provide means under the control of the operator at the different positions to increase the intensity of the over-load characterization of the signals, so that the operator when attending the answering of one 10 call will preferably, by the operation of her operator's telephone set connecting mechanism herein illustrated as operators' listening keys, cause all of the signals associated with calling telephone lines on her position to indicate an additional measure of over-load. My invention, therefore, is capable of 15 being exercised in two forms, and each form 20 may be employed independent of or with the other form.

Other objects of my invention and the invention itself will be better understood from 25 the description of the same which follows, reference being had to the drawing accompanying this specification in which I show at A and B two telephone stations comprising a hookswitch having contacts *c* and a telephone set *r*, these being connected by line conductors leading to a main telephone exchange, the station A being connected on a line L_2 and the station B being connected on a line L_1 , the lines being extended at the 30 main exchange to terminate in multiple switchboard jacks MJB and CJB for the line L_1 , and MJA and CJA for the line L_2 . The multiple jacks MJB and MJA for the lines are shown as having no signal lamps 35 associated with them, since they are merely for the purpose of permitting connection to be made to the associated line when the said line is a called line. However, the multiple jacks CJB and CJA of the lines have associated with them multiple lamps CLB and CLA, one signal lamp for each jack. These 40 last-named jacks are located on switchboard sections variously known in the art as "helping" sections, "concentration" sections, or "associated" switchboard sections. 45

At C, I show for the line L_1 what is known in the art as an intermediate cross-connecting rack on which the line may be cross-connected to different answering terminals. 50 The line L_1 at C is cross-connected by means of conductors 37, 38, 39 and 40 extending between terminals 25, 26, 27 and 28, to terminals 13, 14, 15 and 16 to the answering jack J^b having an answering signal lamp 55 LB, and to the line and cut-off relays associated therewith LRB and COR.

It is very desirable in the system of my invention that the line and cut-off relays of the lines be permanently associated with the 60 answering terminals as has been described,

rather than in accordance with the more common practice of permanently associating them with the multiple switchboard jacks and connected line conductors. The reason for this is to preserve the proper characterization of the lamps as will be described, regardless of the cross-connections which may be at the intermediate frame.

In this description it is assumed that the answering terminals of the line L_1 and of the line L_2 are located on the same operator's position, and that other lines not shown also terminate in like manner in this operator's position, also that the multiply connected lamps and their associated multiple jacks of the lines leading into the exchange are variously located on the multiple and concentration sections of the switchboard, with or without regard to the location of their answering terminals.

In order to better understand the invention I will now described the same, referring to the operation of the apparatus involved in greater detail.

Assume that a subscriber on the line L_2 makes a call to the exchange, he will take his receiver from the hook closing the contacts *c* of the hookswitch, place his telephone set *r* in conversational circuit across the line L_2 which leads by its conductors 80 and the cross connection wires 35 and 36, to the call answering apparatus at the exchange.

The line conductors are continued by conductors 62 and 63 through contacts 58 and 59 to the line relay LRA which will now be energized closing its contacts 2 whereupon the line lamps associated with the line will be lighted to give a signal. All of the line lamps which are three in number as shown in the embodiment in the drawing, will be so operated over a circuit traced as follows: from the negative pole of the source of current S to several branches of a divided circuit, each leading to the conductor 54 one branch including the winding SR of a double wound relay common to the operator's position and a conductor 50, and another branch including a conductor 52 and a circuit interrupter I which intermittently interrupts the circuit of the conductor 2, and thus intermittently short circuits the winding SR of the double wound relay. A third branch includes the resistance R together with circuit conductors leading through contacts 71, 72 and 73 on the operators' listening keys of the position, whereby through the said key contacts the said resistance is placed in multiple with the winding SR, and when the interrupter I is not short circuiting the winding SR, the inclusion of this resistance coil in multiple circuit with the circuit SR modifies the effect thereof in a manner to be later described, this modification being controllable by the operation in ma-

nipulating the listening keys K_1 , K_2 and K_3 which contain the contacts 71, 72 and 73 in the circuit of the resistance coil R .

It will be noted that when these contacts 5 are all closed indicating an idle condition of the operator, that the shunting of SR by R will reduce the resistance effect of SR , and that when all the contacts of the listening keys above mentioned are opened the removal of this shunt about the resistance winding SR will restore it to its full resistance effect.

In practice I may dispense with either the resistance winding SR or the resistance coil 15 R , together with its associated key contacts, entirely. But I may as illustrated in this embodiment of my invention, use the two together, the one modifying the effect of the other; the particular arrangement used depending upon the conditions local to the exchange and the results desired to be secured.

We will assume now that another subscriber on the line L_1 , such as the subscriber 25 B initiates a call, and by closing the switch-hook contacts c places his set r across the telephone line conductors which extend by the cross connecting wires 39 and 40 and the circuit conductors 60 and 61, through contacts 30 56 and 57 to the line relay LRB of the line and the source of current S included in circuit therewith energizes the line relay, closing its contacts 3 in the circuit of the answering lamp LB , and the concentration 35 lamp CLB in multiple, the circuit being traced as follows: From the ground pole of the source of current S through the lamps CLB and circuit conductors 45 and 37 in multiple with the lamp LB , the terminal 13 40 of the cross connecting rack C , circuit conductor 48, contacts 3 of the line relay LRB , and common circuit conductor 55 leading through the low resistance winding of the double wound relay to the circuit conductor 45 54 and from thence through the winding SR , the interrupter I and the resistance coil R all in multiple, to the negative pole of the source of current S .

It will be seen that under the assumption 50 that the first call has not been answered, that there are now two calls on the operator's position and six lamps associated with two calling lines are operated, the energizing circuit of all of the lamps including in common the resistance coil SR which is shunted by the resistance coil R and the intermittently short circuiting interrupter I . The drop in voltage across the resistance being expressed by the formula voltage equals current times resistance, is thus proportional to the current flow through the resistance, and therefore the drop of voltage across the shunting resistance SR is nearly double that caused by the lighting of lamps of one line; 55 and the inclusion of this resistance in cir-

cuit with these lamps will quite noticeably dim the lamps by reducing the effective voltage energizing them. The interrupter I now intermittently short circuiting the serially included resistance will intermittently eliminate the drop in voltage restoring the effective voltage to light the lamps to normal value, and thus will intermittently cause a noticeable flashing of the lamps from subnormal to normal brilliancy.

In the operation of the system, we will now assume that the operator will by means of the connecting circuit, not shown, make connection with one of the calling lines and will operate her listening key K_2 with the 80 said connecting circuit breaking the contacts 72 therein contained and which are serially included with the resistance coil R in the shunting circuit about the terminals of the resistance winding SR in the lamp circuit. The elimination of this resistance coil from about the terminals of the resistance SR is effective to increase the common resistance serially included with the lamps of the remaining unanswered calling line, the 85 lamps of the answered line having been extinguished in the ordinary way by the act of the operators making connection with the line and releasing the line relay thereof.

Now, the resistance of the coil R may be 95 proportioned to produce various effects. But I prefer to make it of about the same resistance as the winding SR , so that when the operator is attending to a call the effect of the resistance SR is double, that is, the 100 resistance SR will be double that of the combined resistance of SR and R in multiple; therefore with one unanswered calling line and one call being answered the effect on the lamps of the remaining unanswered line will be modified from the effect which would prevail if the operator did not have a listening key thrown, the modification being in the direction of increased flashing, that is, increased variation in brilliancy. This variation may be as has been above indicated modified to any suitable degree by the relative and quantitative values chosen for the resistances R and SR .

Other lines may also lead into the operator's position and a portion of a third line is indicated by its cross-connecting wires 29, 30, 31 and 32, being shown as extending between the set of terminals 17, 18, 19 and 20 on the line side, and the set 5, 6, 7 and 8 on 115 the answering switchboard side of the cross-connecting rack. The common circuit conductor 55 in the signalling circuit divides to connect with the line lamps of all of the lines in the group served by the same common apparatus, and which are preferably those belonging to a given operator's position.

It is obvious from the foregoing description that the system herein disclosed is not 130

only capable of giving the lamps of a line on a busy position an indication of the busy condition, but also is capable of indicating the measure of the busy condition of such a position.

The concentration sections of the switchboard also have operators' answering equipment placed thereon, and it is the duty of the operators at such positions to answer the calls on lines which have their answering terminals in busy positions, preference in answering at such concentration sections being given to the lines on the position which by the flashing of the lamps indicate the greatest degree of over-loading at the home or answering positions. In this way these concentration operators or helping operators are enabled to assist the home operators who are most in need of the help.

It is obvious that many and extensive departures may be made from the embodiment illustrated and described herein without departing from the spirit of the invention. This invention is in the nature of an improvement over the invention disclosed in the co-pending application of William S. Paca, Serial No. 202,748, filed Nov. 19th, 1917, wherein marginal relays are employed to change the character of the extended signal on the associated switchboard whenever a predetermined load has been exceeded on the main switchboard. In the system of my invention I do away with the marginal relays and the necessity of special relay adjustments, and secure new results over that secured in the invention of Paca.

What I claim as my invention is defined in the following claims:

1. In a telephone system, the combination of a main switchboard and an associated switchboard, of telephone lines each terminating at each switchboard in connection switches, of individual signal lamps at each switchboard for each of the said connection switches, sub-station apparatus for each of the lines to cause the operation of its associated signal lamps, and common controlling means quantitatively responsive to the total number of signal lamps operated to correspondingly vary the quantitative character of the signal given by the said lamps.

2. In a telephone system, the combination of a telephone switchboard divided into normal answering and abnormal helping sections, of a plurality of telephone lines terminating at each of the switchboards in multiple connection switches, of individual signal lamps for each of the lines associated with the said switches, and common controlling means quantitatively responsive to the number of signal lamps operated, quantitatively controlling the said lamps.

3. In a telephone system, the combination with a telephone switchboard divided into normal answering and associated helping

sections, of a plurality of telephone lines terminating at the normal answering section in terminals of connection switches, of signal lamps for each of the lines associated with the said terminals, of multiple terminals for each of the lines at the said helping switchboard section, a resistance unit in the circuit of all the lamps of a group terminating in the said answering switchboard section and in the circuit of the associated lamps at the helping switchboard section, and an intermittently operated shunt for the said resistance unit, said intermittently operated shunt being operated at such a rate as to flash the said lamps.

4. In a telephone system, the combination with a plurality of telephone lines and a plurality of multiply connected signal lamps, of a circuit for said multiply connected lamps, a resistance unit in said circuit, a source of current in said circuit, means controlled over a telephone line for closing said circuit and an intermittently applied shunt for the said resistance unit, said shunt being applied at such a rate as to flash the said lamps.

5. In a telephone system, the combination with a plurality of multiply connected switchboard lamps, of a resistance unit and a source of current in the common circuit thereof, an intermittent shunt for the said resistance unit, and a manual switch for varying the quantitative value of the said resistance unit.

6. In a telephone system, the combination with a plurality of telephone lines and signal lamps, of a source of current and a resistance unit, an individual switch for each lamp to connect the same in operative circuit with said source of current through said resistance unit, means controlled over said telephone line for closing said individual switch, and an intermittently operated shunt for the said resistance unit, said shunt being adapted to flash the said lamps.

7. In a telephone system, the combination with a plurality of signal lamps, of a double wound pilot relay and a source of current, an individual switch for each of the said lamps to connect the same in operative circuit with the said source of current through both of the windings of the said double wound relay, and an intermittently operated shunt for one of the said windings.

8. In a telephone system, the combination with a plurality of signal lamps, of a double wound pilot relay and a source of current, an individual switch for each of the said lamps to connect the same in operative circuit with the said source of current through both of the windings of the said double wound relay, an intermittently operated shunt for one of the said windings, and a pilot lamp controlled by an armature of the said double wound relay.

9. In a telephone system, the combination with a plurality of signal lamps, of a double wound pilot relay and a source of current, an individual switch for each of the said 5 lamps to connect the same in operative circuit with the said source of current through both of the windings of the said double wound relay, an intermittently operated shunt for one of the said windings, and a 10 resistance unit normally connected in operative relation to the intermittently shunted winding of the double wound relay to change the quantitative resistance character thereof, and manual means for removing the said 15 resistance unit from operative relation to the said winding.
10. In a telephone system, the combination of a plurality of signal lamps, a source of current and a resistance unit, an individual 20 switch for each lamp to connect the same in operative circuit with the said source of current through the said resistance unit, an intermittently operated shunt for the said resistance unit, a second resistance unit oper- 25 atively associated with the said first-named resistance unit to vary the character thereof, and a manually operated switch to dissociate the said second-named resistance unit from said first-named resistance unit.
- 30 11. In a telephone signalling system, of a group of signal lamps, of a second group of signal lamps each of which is adapted to be interchangeably connected with the lamp of the first group, of a source of current and a resistance unit, an individual switch for each 35 pair of the associated lamps to operatively associate the said pair of lamps with the said source of current through the said resistance unit, and an intermittently operated shunt for the said resistance unit, said shunt being 40 operated at such a rate as to flash the associated lamps.
12. In a telephone system, the combination with a plurality of telephone lines and a plurality of multiply connected signal 45 lamps, of a resistance unit, a circuit for said multiply connected lamps including said resistance unit, a source of current therein, means controlled over a telephone line for closing said circuit, an intermittently oper- 50 ated shunt for the said resistance unit and switching means to vary the number of multiply connected lamps, said shunt being applied to the said resistance unit at such a rate as to operatively flash the said lamps. 55

In witness whereof, I hereunto subscribe my name this 3rd day of December, A. D. 1917.

FRANK M. SLOUGH.
